INVENTOR

UNITED STATES PATENT OFFICE

HOWARD S. NEIMAN, OF BROOKLYN, NEW YORK

LOOSE POWDER CONTAINER

Application filed December 14, 1929. Serial No. 414,194.

My invention relates to powder containers and refers particularly to containers adapted for containing loose powder.

While it is generally admitted that loose face powders are more desirable than face powders in solid, or compact form, the adoption of the former has not been more general because of its liability to sift out of the containers during their period of non-use.

Attempts have been made to overcome this difficulty by constructing containers having two foraminous plate covers, the openings of which are capable of being placed in alignment to allow the escape of the powder and into non-alignment to prevent such powder escape.

The device of my invention belongs to this class of powder containers but possesses advantages not found in the prior devices, in that the unfastening of the container cover automatically ejects a predetermined portion of powder, the openings being in non-alignment when the cover is closed, thus preventing the escape of powder during the closed period, and the openings being also in closed position when the device is open, thus preventing the escape of powder during the open period of the device.

It will thus be seen that my device possesses the advantage of preventing the escape of powder during both open and closed periods of the container while forcing powder outwardly during the period in which the cover is passing from closed to open position.

It will be noted further that but one movement is necessary to open the container and eject the powder.

The above mentioned and other valuable attributes of my device will be evident upon a consideration of my specification and its accompanying drawings.

In the accompanying drawings illustrating one form of the device of my invention, similar parts are designated by similar numerals.

Figure 1 is a front view of one form of my device in closed position.

Figure 2 is a rear view of the device of Figure 1.

Figure 3 is a side view of the device of Figure 1 with the loading side open.

Figure 4 is a section through the line 4—4 of Figure 5.

Figure 5 is a section through the line 5—5 of Figure 4.

Figure 6 is a section through the line 6—6 of Figure 5.

Figure 7 is a section through the line 7—7 of Figure 4.

Figure 8 is a section through the line 8—8 of Figure 5.

Figure 9 is a perspective view of the locking and disk moving mechanism.

Figure 10 is a perspective fragmentary view of the three-casing elements.

Figure 11 is a top view of the resilient member of the loading compartment cover.

The particular form of the device of my invention shown in the accompanying drawings comprises a powder receptacle having the annular side 20 carrying the extended lip 21 within which is an opening 22 and having the cut-out, or recess, 23.

Positioned within the upper portion of the side 20 is an annular ring 24 maintained in place by frictional contact or by means of the shoulder 25 formed in the side 20.

Supported by the ring 24 are two foraminous plates 26 and 27, revolvably maintained with respect to each other by the rivet 28, the plate 26 being retained from revolution by means of the dependent flange 29 and the shoulder 30 of the side 20. The plate 26 has an opening 31 and the flange 29 has a recess, or cut-out, 32A. The periphery of the plate 27 is toothed.

A cover 32 is attached to the side 20 by means of the hinge 33, carrying the coil spring 34, one end 35 of which is anchored below the plate 26 and the other end 36 of which abuts upon the inner face of the cover 32. The cover 32 carries the dependent hook 37. A mirror 38 is carried upon the inner face of the cover 32.

The means for revolving the plates 26 and 27 with respect to each other and unlocking and locking the cover 32 comprises an arc-shaped member 39 having the lip 40 carried by the member 39, and, spaced therefrom by the spacer 41 is an arc-shaped member 42 and attached to the inner face of the member 100

is a ratchet-operating member 43 having the extended portion 44. The members 39, 41, 42 and 43 are attached to each other by the rivet 45.

5 A cover for the powder receptacle comprises the top 46 and the flange 47, the flange having the extended portion 48, the opening 49 and the recess, or cut-out, 50. A hinge 51 connects the flange extension 48 with the side 20, the hinge thus being above the split-line between the side 20 and the cover 46.

15 Fixedly attached to the inner side of the cover top 46 by means of a rivet 51, is an armed spring 52 and a cup 53, the latter having a plurality of outwardly extended prongs 54, 54.

20 Positioned around and slidable upon the cup 53 is a pressure plate 55 which is retained from disengagement by the prongs 54, 54.

25 The locking member for the powder receptacle cover comprises a flat spring 56 having the projection 57 and anchored to the inner face of the flange 47 by the rivets 58, 58.

30 The free end of the spring 56 has a rivet 59 carrying the extended locking member 60 which, in normal position, passes through the hole 22 of the side 20, but which may be pressed inwardly by an inward movement of the projection 57 thus removing the locking member 60 from within the hole 22.

35 The operation of the device is as follows:—

40 To insert powder, the device is positioned as shown in Figure 3, that is, with the powder receptacle cover uppermost. The projection 57 is pressed inwardly thus removing the locking member 60 from within the opening 22 thus unlocking the cover. The cover is then opened, as shown in Figure 3, powder introduced and the cover closed. The powder 45 is thus positioned between the pressure plate 55 and the foraminous plates 26 and 27, the pressure plate forcing the powder against the foraminous plates.

45 When in this position the openings 61, 61 of the plate 27 and the openings 62, 62 of the plate 26 are in non-alignment with each other and hence the powder can not escape therethrough.

50 The projection 40 of the locking member is now moved along the opening 23 of the side 20 in the direction of the arrow shown in Figure 5, thus moving the entire locking member. The end 44 of the spring 43 abuts 55 upon one of the teeth, or ratchets, 63, 63 of the plate, and the movement of the locking member thus causes the revolution of the plate 27. The teeth 63, 63 and the openings in the plates 26 and 27 are so positioned that the 60 full movement of the locking member will cause the openings to pass from closed position through open position to closed position. Hence, during the movement of the locking member, powder will be forced outwardly 65 through the aligned openings, said openings

being closed at both extreme positions of the locking member.

When the locking member is in position prior to the movement just described, the hook 37 of the cover 32 is positioned below the member 42, as shown in Figure 9, and hence the cover is maintained in locked closed position. During the described movement of the locking member, the member 42 slides through the hook 37, until it has passed completely therethrough, when the hook 37 is released and the cover 32 opens through the medium of the spring 34.

75 It will thus be seen that when the device is in closed and locked position, the openings 61, 61 and 62, 62 are not in alignment and hence powder can not pass therethrough and that the movement of the locking member forces powder through these openings upon the under face of the powder puff 66, then closes the openings and opens the cover 32.

80 When the powder has been employed, the puff 66 is replaced, the cover 32 placed in closed position and the locking member returned to its original position, the member 44 returning into position against the next tooth 63 for the next operation, the member 42 locking the cover 32 in closed position.

85 It will be noted that no powder is ejected during the closing period, and hence the device must be completely closed before further powder is obtainable.

90 It will be further noted that if the cover is partially opened, then closed and then completely opened, the same amount of powder 95 will be ejected as would have been caused by a complete opening in the first movement.

95 My invention, therefore, presents a device whereby a predetermined amount of loose powder will be ejected from the mass contents by a complete movement of the cover 105 from a closed position to a full open position, irrespective of the cover movements between these two positions.

100 I do not limit myself to the particular size, shape, number or arrangement of parts as shown and described as these are given simply as a means for clearly explaining the device of my invention.

110 What I claim is:—

115 1. In a device of the character described, in combination, a casing, a fixed foraminous plate within said casing, a revoluble foraminous plate abutting upon the under face of said fixed plate, a vertically movable pressure plate spaced below said revoluble plate, resilient means for moving said pressure plate, means allowing the insertion of loose powder between said revoluble plate and said pressure plate, a cover for said receptacle, means for fastening said cover in closed position and means whereby unfastening said closed cover will move said revoluble plate, causing the openings in the two foraminous 120

125 130 135 plates to pass from closed position through open position to closed position.

plates to pass from non-alignment, through alignment to non-alignment positions.

2. In a device of the character described, in combination, a casing, a fixed foraminous plate within said casing, a revolute foraminous plate abutting upon the under face of said fixed plate, a vertically movable pressure plate spaced below said revolute plate, resilient means for moving said pressure plate, means allowing the insertion of loose powder between said revolute plate and said pressure plate, a cover for said receptacle, means for fastening said cover in closed position and ratchet means whereby unfastening said closed cover will move said revolute plate, causing the openings in the two foraminous plates to pass from non-alignment, through alignment to non-alignment positions.

29 3. In a device of the character described, in combination, a casing, a fixed foraminous plate within said casing, a revolute foraminous plate abutting upon the under face of said fixed plate, a vertically movable pressure plate spaced below said revolute plate, resilient means for moving said pressure plate, means allowing the insertion of loose powder between said revolute plate and said pressure plate, a cover for said receptacle, means for fastening said cover in closed position, means whereby unfastening said closed cover will move said revolute plate, causing the openings in the two foraminous plates to pass from non-alignment, through alignment to non-alignment positions, and means whereby said revolute plate will not be moved during the fastening of said cover.

4. In a device of the character described, in combination, a casing, a fixed foraminous plate within said casing, a revolute ratchet foraminous plate abutting upon the under face of said fixed plate, a vertically movable pressure plate spaced below said revolute plate, resilient means for moving said pressure plate, means allowing the insertion of loose powder between said revolute plate and said pressure plate, a cover for said receptacle, movable fastening means retaining said cover in closed position, and means carried by said fastening means capable of co-acting with said ratchet revolute plate during the movement of said fastening means to move said revolute plate causing the openings in the two foraminous plates to pass from non-alignment, through alignment to non-alignment positions.

5. In a device of the character described, in combination, a casing, a fixed foraminous plate within said casing, a revolute ratchet foraminous plate abutting upon the under face of said fixed plate, a vertically movable pressure plate spaced below said revolute plate, resilient means for moving said pressure plate, means allowing the insertion of loose powder between said revolute plate

and said pressure plate, a cover for said receptacle, movable means for fastening and unfastening said cover in closed position, resilient means operated by said fastening means to revolve said revolute plate during the movement from fastened to unfastened position of the cover and allowing said revolute plate to remain stationary during the movement from unfastened to fastened position of the cover.

6. In a device of the character described, in combination, a casing, a fixed foraminous plate within said casing, a revolute foraminous plate abutting upon the under face of said fixed plate, a vertically movable pressure plate spaced below said revolute plate, resilient means for moving said pressure plate, means allowing the insertion of loose powder between said revolute plate and said pressure plate, a cover for said receptacle, movable means for fastening and unfastening said cover in closed position and means whereby the movement of said fastening means will force powder through the aligned openings of the two said plates during the unfastening period.

7. In a device of the character described in combination, a casing, a fixed foraminous plate within said casing, a revolute foraminous plate abutting upon the under face of said fixed plate, a vertically movable pressure plate spaced below said revolute plate, resilient means for moving said pressure plate, means allowing the insertion of loose powder between said revolute plate and said pressure plate, a cover for said receptacle, movable means for fastening and unfastening said cover in closed position and means whereby the movement of said fastening means will cause a non-alignment of the openings in the two plates when the cover is in fastened closed position.

8. In a device of the character described, in combination, a casing, a hinged bottom to said casing, a vertically movable pressure plate carried by said bottom, resilient means for moving said pressure plate, a revolute foraminous plate positioned above and spaced from said pressure plate, a fixed foraminous plate positioned above and abutting upon the upper face of said revolute plate, a hinged cover above and spaced from said fixed plate, movable means fastening the cover in closed position when the openings in the two said plates are in non-alignment, and means whereby the cover can be opened when the openings in said plates have been moved from said non-alignment, through alignment to non-alignment positions.

9. In a device of the character described, in combination, a casing, a hinged bottom to said casing, a vertically movable pressure plate carried by said bottom, resilient means for moving said pressure plate, a revolute

- foraminous plate positioned above and spaced from said pressure plate, a fixed foraminous plate positioned above and abutting upon the upper face of said revoluble plate, a hinged cover above and spaced from said fixed plate, and means whereby said cover can not be fastened in closed position when the openings in the two plates are in alignment with each other.
10. In a device of the character described in combination, a casing, a fixed foraminous plate within said casing, a revoluble foraminous plate abutting upon the under face of said fixed plate, a powder chamber beneath said revoluble plate, said revoluble plate forming the upper cover of said powder chamber, means allowing the insertion of loose powder into said powder chamber, a cover for said receptacle, means for fastening said cover in closed position and means whereby unfastening said closed cover will move said revoluble plate causing the openings in the two foraminous plates to pass from non-alignment through alignment to non-alignment positions.
11. In a device of the character described, in combination, a casing, a fixed foraminous plate within said casing, a revoluble foraminous plate abutting upon the under face of said fixed plate, a powder chamber beneath said revoluble plate, said revoluble plate forming the upper cover of said powder chamber, means allowing the insertion of loose powder into said powder chambers through the lower portion of said casing, a cover for said receptacle, means for fastening said cover in closed position and means whereby unfastening said closed cover will move said revoluble plate causing the openings in the two foraminous plates to pass from non-alignment through alignment to non-alignment positions.
12. In a device of the character described containing a casing, a cover therefor and two foraminous plates, means whereby the unfastening of the cover from the casing will cause the openings in said plates to pass from non-alignment through alignment to non-alignment positions.
13. In a device of the character described, a casing, a cover for said casing, means adapted for fastening and unfastening said cover to said casing, two foraminous plates within said device, means whereby the openings in said foraminous plates are in non-alignment when said fastening means is in fastening position and means whereby the movement of said fastening means will cause said openings to move to aligned position.
14. In a device of the character described, a casing, a cover for said casing, means adapted for fastening and unfastening said cover to said casing, two foraminous plates within said device, means whereby the openings in said foraminous plates are in non-

alignment when said fastening means is in fastening position and means whereby the movement of said fastening means from fastening position to unfastening position will cause said openings to move to aligned position.

15. In a device of the character described, a casing, a cover for said casing, means adapted for fastening and unfastening said cover to said casing, two foraminous plates within said device, means whereby the openings in said foraminous plates are in non-alignment when said fastening means is in fastening position and means whereby the movement of said fastening means will move one of said plates with respect to the other of said plates.

16. In a device of the character described, a casing, a cover for said casing, means adapted for fastening and unfastening said cover to said casing, two foraminous plates within said device, means whereby the openings in said foraminous plates are in non-alignment when said fastening means is in fastening position and means whereby the movement of said fastening means will cause a change of position of said plates with respect to each other.

17. In a device of the character described, in combination, a casing, a cover for said casing, means adapted for fastening and unfastening said cover to said casing, two foraminous plates and means whereby a movement of said fastening means will cause the openings in said plates to pass from non-alignment to alignment.

18. In a device of the character described, in combination, a casing, a cover for said casing, means adapted for fastening and unfastening said cover to said casing, two foraminous plates and means whereby a movement of said fastening means will cause a relative movement between the two said plates with respect to each other.

Signed at New York city in the county of New York and State of New York this 13th day of December, 1929.

HOWARD S. NEIMAN.
